ACETYLENE-GAS LAMP.

1,130,339.

Specification of Letters Patent.

Patented Mar. 2, 1915.

Application filed August 11, 1914. Serial No. 856,215.

To all whom it may concern:

Be it known that I, GERMAIN ROUSSEL, a citizen of the Republic of France, residing at Broughton, in the county of Allegheny and 5 State of Pennsylvania, have invented certain new and useful Improvements in Acetylene-Gas Lamps, of which the following is a specification.

The present invention relates to improvements in acetylene gas lamps and is designed to provide a compactly arranged portable or pocket lamp that will generate its own gas and be self-contained in all particulars.

15 The invention consists essentially in certain combinations and arrangements of parts as will be hereinafter specifically pointed out and claimed.

In the accompanying drawings I have 20 illustrated one complete example of the physical embodiment of my invention constructed according to the best mode I have so far devised for the practical application of the principles of the invention.

25 Figure 1 is a top plan view of a lamp constructed according to and involving the principles of my invention. Fig. 2 is a front elevation of the lamp. Fig. 3 is a vertical sectional view of the lamp of Fig. 1 on line 30 1—1. Fig. 4 is an enlarged detail view of the snap fastening between the water tank and the carbid tank. Fig. 5 is a face view of the fastening. Fig. 6 is an enlarged view of the water feed regulating device. Fig. 7 35 shows a portion of the gas pipe in section with a strainer therein. Fig. 8 is a plan view of one of the strainer disks.

In the preferred embodiment of my invention as shown in the drawings I have 40 illustrated a water feed type of generator and to provide for the separate compartments or vessels I utilize a sectional device comprising the water tank 1 having a closed top and water supply cap 2 through which 45 the water may be supplied to the tank. The tank 1 is closed at its bottom of course, and the bottom 3 forms the top for the open-top carbid tank 4.

The device as a whole is elliptic in cross 50 section, and the two tanks, one above the other, extend from end to end of the ellipse as shown in Fig. 1. To generate gas the water in the tank 1 is fed to the carbid holder or tank 4 through a water pipe 5 which is 55 integral with or fixed to the underside of

the bottom 3 of the tank 1. Directly above the upper open end of this pipe 5, a beveled edge opening or seat 6 is formed in the bottom of the tank 1, and in this seat the correspondingly beveled edge of a hollow plug 60 or pipe 7 is adapted to co-act to regulate the passage of water from the water tank through the seat 6 and pipe 5 into the carbide holder.

At its upper end the hollow plug 7 is 65 formed with external threads 8 and a perforated knurled head 9, and by turning the knurled head the threads 8 may be turned in the threads 10 of an annular flange in the top of the tank 1, to regulate the passage of 70 water to the carbide holder. A stirrer or stirring rod 11, with a handle 12, and a bent end 13 in the carbide holder may be turned to agitate the lumps of the carbide to prevent them massing together. 75

In Figs. 4 and 5 the spring fasteners for holding together the water tank and the carbide tank or holder are illustrated. A spring latch 14 is attached securely to the tank 1 and its lower end is formed as a hook 80 15 which is adapted to pass through a loop 16 riveted to the carbide holder and properly positioned to receive the latch. As many of these hooked latches may be utilized as is required to hold the two tanks securely in 85 place and insure a joint between them that will prevent escape of gas as it is generated in the tank 4.

A gas pipe 17 leads from the tank 4 and 90 conducts the generated gas to the burner 18 which is of usual or suitable type and is located in a reflecting chamber 19 in the front of the lamp. A mirror 20 or other reflector is located back of the lamp in said chamber and the front of the chamber is closed by a 95 glass plate 21. This glass plate 21 is held in a slot 22 in the top 23 of the lamp closure and is held at the bottom by a catch or clamp 24 of usual or suitable type so that it may be released and lifted through the 100 slot 22 in order to gain access to the interior of the reflecting chamber 19 to ignite the gas as it emerges from the burner 18. An igniter 25 of the steel milled wheel type which frictionally engages a flint, is located in operative proximity to the burner so that the gas may be ignited, and the usual disk 26 with its perforations and cotton strainer 27 are provided in the gas pipe to strain the generated gas. 110

A pivoted handle 28 is attached to the tank 1 and this may be swung out of the way when not in use, as shown in Fig. 2, a bent portion 29 being used in the handle to engage a recess 30 in the tank wall to hold the handle in inoperative position.

It will be understood that the two tanks are held together by the locking spring catches or hooks and that the tank 1 has a 10 projecting top portion 23 while the tank 4 has a projecting bottom portion 31 between which, projecting portions the reflecting chamber is located, and the glass plate 21 which closes this chamber is rounded to conform to the outline of the device.

A gasket 32 may be utilized between the two beveled edges of the adjoining tanks (see Fig. 4) to insure a gas tight joint, and other minor details of construction, which 20 have not been illustrated, will of course be embodied in the actual physically constructed device.

From the above description taken in connection with the drawings it is obvious that 25 I have provided a combination of elements

that furnish a device that may be manipulated with facility, maintained with economy, and operated with efficiency; and which will prove highly desirable for performing the functions for which it is best suited.

Having thus fully described my invention, what I claim as new and desire to secure by Letters Patent is:—

A portable gas lamp of elliptical cross 35 section comprising in combination a water tank with a slotted projecting top and a lower carbide tank with a projecting bottom and means for detachably fastening said parts together, a movable plate glass front 40 in the slotted top resting on the bottom forming a reflecting chamber, a gas burner in the reflecting chamber, and a reflector at the rear of the burner.

In testimony whereof I affix my signature 45 in presence of two witnesses.

GERMAIN ROUSSEL.
